UNITED STATES PATENT OFFICE.

JOHN J. KENNEDY, OF NEW YORK, N. Y.

METHOD OF CONSTRUCTING UNDERGROUND TUNNELS.

Application filed March 23, 1925. Serial No. 17,506.

This invention relates to a method of constructing underground tunnels of concrete or other similar material in transverse as well as longitudinal sections contemporaneously with the digging thereof, with the object in view of providing procedures and arrangements whereby only a sufficient opening is made to receive a form and its support into which form the fluid or plastic concrete is poured or deposited.

Another object is to provide a method in which the preliminary structure minimizes the materials used, thereby effecting an economy in labor and cost of production.

Another object is to provide a method in which the preliminary structures may be easily handled to accomplish speedy erection with the maximum assurance of safety.

It has previously been the custom in tunnel building to remove or clear the material to form an opening substantially the width and height desired and to the level of the proposed floor of the tunnel.

Moreover to overcome this and other difficulties to a great extent a large amount of matter, in excess of that necessary for the tunnel proper, must be removed to accommodate temporary shields for the workmen employed in the excavation which is to receive the side walls etc. of the tunnel. While removing the matter, such as rock, stones, etc., the excavators are placed in great danger owing to the fact that the roof of the opening is unsupported and, in order to guard against "cave ins" etc. a great quantity of timber must be used for shoring the roof and side walls of the opening.

When the forms for lining the tunnel proper with concrete are placed in position, certain portions of the preliminary shoring must be removed from time to time and replaced after the concrete form has become hard and dry. This procedure not only requires considerable amount of materials to erect the necessary structures but it also consumes a vast amount of time as well as requiring a great number of skillful workmen to complete the operation.

Furthermore, the common practice in tunnel building is to first form the bench or side walls, thence the upper walls and crown of the arch, and lastly the key to the arch is formed between the oppositely disposed walls forming the crown.

In my improved method of constructing underground tunnels, I cut small longitudinal openings, support the top of each of the openings, form and finish in concrete each section of the tunnel which is to be built in its opening, until the transverse section of the arch is completed to the floor line.

A practical embodiment of my invention is represented in the accompanying drawings, in which

Fig. 1 represents a perspective view of my improved method of tunnel construction, showing a transverse section of the tunnel.

Fig. 2 represents a vertical longitudinal section taken in the plane of the line II—II of Fig. 1, looking in the direction of the arrows.

Fig. 3 represents a detail vertical section taken in the plane of the line III—III of Fig. 2, looking in the direction of the arrows, and

Fig. 4 represents a modified form of double tunnel construction.

Referring to Figs. 1 to 3 inclusive of the drawings, in constructing the tunnel by my improved method, I first remove sufficient material, such as stones, rocks, or earth, etc. to form a longitudinal opening of such size as will permit the workmen to carry on the further operations. I then proceed to temporarily locate longitudinal wall plates denoted by 1, 2 upon opposite sides of the opening, which wall plates serve as a base to receive legs 3 which support transversely disposed cap beams 4. These cap beams are arranged in close proximity to each other and serve to hold the roof of the opening from caving in or falling upon the workmen employed in the opening. After the roof has been supported, the opening may be extended downwardly to the proposed floor line or to a predetermined level and vertical posts 5 may be erected to shore the wall plates 1, 2. Upon arriving at the predetermined level, I now proceed to erect a bent or truss upon which is to receive a form for the key section 6 of the tunnel. This form comprises a curved bottom 7, radially disposed side walls 8, 9, and a vertical end wall 11, as clearly shown in Figs. 2 and 3. The bottom 7 of the form may be built of lagging and spaced a predetermined distance below the transverse cap beams 4. The

bottom 7 rests upon a plurality of arch pieces 12 arranged at intervals throughout its length. The arch pieces 12 are secured to longitudinal stringers 13 mounted on cap beams 14, supported from the floor plates 15 by posts 16 of the bent. These posts are rigidly held in place by transverse cross braces 17, 18, tie braces 19, and by longitudinal tie beams 20, 21.

In order to lock the key section 6, both transversely and longitudinally to the adjacent key sections, I provide each of the side walls 8, 9 of the form with a longitudinal rib 22, which rib develops a longitudinal recess 23 in the sides of the key section 6. The end wall 11 is provided with a transverse rib 24 arranged to form a recess 25 for coacting with the adjacent key section. After the form has been located in place it is filled with liquid or plastic concrete in any well known or approved manner, and when the concrete is hard and dry, the operation of removing the material adjacent the newly constructed key section is continued. As the material is removed from the side of the key section, I insert a series of longitudinal crown bars 26 which are held in place by struts 27 carried by the wall plates. These crown bars 26 serve to prevent the roof of the opening from falling while the further operation progresses. When the desired opening has been excavated and the crown bars 26 located in position, the longitudinal side wall 9 of the form is removed to expose the side of the key section with its longitudinal recess.

A form 28 shown in Fig. 1 of usual construction and supported in any well known or approved manner, is erected a predetermined distance below the crown bars and arranged to coact with the bottom 7 of the key section 6. The liquid or plastic concrete is deposited in the last named form and produces a section 29 which serves as the crown of the tunnel and which is locked to the key section 6 by the longitudinal recess 23 and its adjacent wall.

The side wall 30 of the tunnel is similarly constructed by removing the material, after the crown section 29 is hard and dry, erecting and supporting a form 31 and filling the form with concrete.

In the form shown in Fig. 4, I have illustrated a double tunnel, and the method of procedure in constructing the same is similar to that hereinbefore described, with respect to the single tunnel, except that I first construct the central wall 32 and then proceed to develop the tunnels on opposite sides of the wall 32.

It will be seen from the above description that the transverse and longitudinal sections of the tunnel will be constructed contemporaneously with the excavating thereof, and that it will not be necessary to remove

any greater quantity of material other than that needed for producing the predetermined excavation.

From the above description taken in connection with the drawings, it will be evident that the method of construction is extremely simple and economical in the cost of material and labor. Furthermore, the method may well be carried out by relatively unskilled labor, the shoring forming at all times a maximum assurance of safety against the caving in of the roof of the excavation.

I contemplate that various changes may be resorted to in the form, construction and arrangement of the several parts used in carrying out the method, without departing from the spirit and scope of my invention; hence, I do not wish to limit myself strictly to the form herein shown and described, except as they may be included in the claims.

What I claim is:—

1. The method of constructing underground tunnels comprising, cutting a longitudinal opening, progressively inserting a series of transversely arranged cap beams in close proximity to each other to support the top of said opening, locating a longitudinal form a predetermined distance below said series of cap beams, and filling the form and embedding the cap beams in concrete to construct the key of the tunnel.

2. The method of constructing underground tunnels comprising, cutting a longitudinal opening, progressively inserting a series of transversely arranged cap beams in close proximity to each other to support the top of said opening, locating a longitudinal form a predetermined distance below said series of cap beams, filling the form and embedding the cap beams in concrete to construct the key of the tunnel, cutting a second opening adjacent one end of the cap beams and at the side of said filled form, progressively inserting a series of longitudinally arranged crown bars to support the top of said last named opening, positioning a form a predetermined distance below said series of crown bars adjacent the longitudinal formed key, and filling the form to the bottom of the crown bars with concrete to construct the crown of the tunnel.

3. The method of constructing underground tunnels comprising, cutting a longitudinal opening, progressively inserting a series of transversely arranged cap beams in close proximity to each other to support the top of said opening, locating a longitudinal form a predetermined distance below said series of cap beams, filling the form and embedding the cap beams in concrete to construct the key of the tunnel, cutting openings adjacent the opposite ends of the cap beams and at each longitudinal side of said filled form, progressively inserting

a series of longitudinally arranged crown bars to support the top of each of the last named openings, positioning a form a pre-determined distance below each of said series 5 of crown bars adjacent each longitudinal side of the formed key, and filling the forms to the bottom of the crown bars with con-

crete to construct the crown of the tunnel on opposite sides of the key.

In testimony, that I claim the foregoing 10 as my invention, I have signed my name this 20th day of March, 1925.

JOHN J. KENNEDY.
